DESIGN FOR A PIN OR THE LIKE

David Staub, United States Navy, assignor to the
Government of the United States of America,
as represented by the Secretary of the Navy

Application August 10, 1942, Serial No. 107,874

Term of patent 14 years

To all whom it may concern:

Be it known that I, David Staub, a citizen of the United States, residing at Washington, District of Columbia, have invented a new, original, and ornamental Design for a Pin or the like, of which the following is a specification, reference being had to the accompanying drawing, forming part thereof.

Fig. 1 is a plan view of a pin or the like, showing my new design, and

Fig. 2 is a sectional view on line 2—2 of Fig. 1.

The essential features of my design reside in the portion shown in full lines in Fig. 1.

While I have shown my design embodied in the form of a pin, it is understood that the same may be embodied in other similar articles without departing from the scope of my invention.

I claim:

The ornamental design for a pin or the like, as shown and described.

DAVID STAUB.
